AUTOMATIC DISPENSING BIN

Charles E. Faulkner, Chicago, Ill., assignor to Spiegel, Inc., a corporation of Delaware

Application February 13, 1956, Serial No. 564,979

7 Claims. (Cl. 221—92)

This invention relates to automatic dispensing bin structure for facilitating filling orders for miscellaneous boxed merchandise from a stock room.

The apparatus of the present invention is particularly designed for large mercantile establishments, such as mail order houses, that keep an open stock of many different items. Mail order houses customarily receive orders for many different items. To fill these orders it is necessary for employees to walk considerable distances, make many stops, and often climb several feet or stoop to pick the individual items from the storage bins. It is often necessary for order pickers to cover the same ground several times in filling a single order. This method of filling orders is relatively expensive because of the waste of manpower.

Another disadvantage inherent in the present method of filling orders is the fact that the height to which the storage bins may be built is limited, because it is recognized that excessive climbing impairs even the moderate efficiency possible where most of the storage bins are within reach of an order picker standing on the floor. The desirability of limiting the height of the storage bins necessitates a greater amount of floor space and also increases the walking distances for the order pickers.

In accordance with the present invention merchandise is removed from the individual bins automatically by remote control and brought to the operator by a conveyor, thereby eliminating all the walking, climbing, and stooping on the part of the order picker.

While the present invention will be described in connection with a single unit comprising a small number of storage bins, it will be understood that the units may have any desired number of individual bins, within reason, and that several units may be used in one stockroom, if desired. Ordinarily each unit comprises at least one hundred individual bins. Conceivably, using an alphabetic control, a unit could consist of 676 individual bins, arranged in 26 rows of 26 bins each.

The dispensing bin structure illustrated in the drawings has six horizontal rows of individual bins with five bins in each row. The horizontal rows are in superimposed relationship, each having six bins aligned vertically with corresponding bins of the other rows to form vertical rows. Each vertical row of bins has a vertical control rod adjacent one side thereof. Six horizontal package restraining levers project laterally from each vertical control rod. The restraining levers of each vertical control rod are aligned and are spaced vertically, with one lever aligned vertically with each of the bins in the vertical row adjacent which the vertical control rod is positioned. In the normal position of the vertical control rods, each of package restraining levers extends laterally in front of the foremost package or box of merchandise in its particular bin. The vertical control rods are selectively rotatable by means of individual solenoids operable by electrical circuits controlled by switches grouped at a central location.

Each horizontal row of bins has a horizontal control

2

rod extending horizontally across the front of each of the bins in its particular row. The horizontal control rods are also rotatable to an inoperative or open position by means of individual solenoids controlled by switches preferably mounted on the same control panel as the switches for the vertical control rods.

Control of actuation is not to be limited to manual manipulation of switches. Such switches could also be manipulated by insertion of tabulating cards, perforated paper tape or other equally efficient means of conversion of data to action initiation signals.

Since the front of each individual bin is normally obstructed by two separate members, the merchandise from any individual bin is dispensed by operating the switches controlling its vertical and horizontal control rods at the same time. For example, if the operator wants a package or box of merchandise stored in the right hand bin in the top row of bins, he presses the switch rotating the vertical control rod adjacent the right hand row of bins and, while holding that vertical control rod in its open or unobstructed position, presses the switch controlling the top horizontal control rod. The merchandise in the selected bin is then free to fall by gravity on to a suitable conveyor while the rest of the bins in the top row are obstructed by the restraining levers projecting laterally from the other vertical control rods, and the rest of the bins in the right hand vertical row are each obstructed by their horizontal control rods.

The structure by which the above mentioned and other advantages of the invention are attained will be described in the following specification, taken in conjunction with the accompanying drawings, showing a preferred illustrative embodiment of the invention, in which:

Fig. 1 is a side elevational view of a dispensing bin structure embodying the invention;

Fig. 2 is a front elevational view of the device shown in Fig. 1, but with the boxes of merchandise omitted for the sake of clarity;

Fig. 3 is a fragmentary front elevational view on an enlarged scale, showing the means for operating the vertical and horizontal control rods;

Fig. 4 is a fragmentary front elevational view showing the upper box being dispensed;

Fig. 5 is a side elevational view of the structure shown in Fig. 4;

Fig. 6 is a fragmentary top plan view showing the means for rotating one of the vertical control rods;

Fig. 7 is a fragmentary cross sectional view, taken along the line 7—7 of Fig. 3; and

Fig. 8 is a diagrammatic view of the wiring circuit for controlling the various solenoids.

In the drawings, the reference numeral 2 indicates a base member having vertical standards 3 and 4 extending upwardly from opposite ends of its front edge. Intermediate vertical standards 5 also extending upwardly from the front edge of base 2 divide the space between standards 3 and 4 into smaller spaces each defining the width of a vertical row of storage bins. The upper ends of standards 3, 4 and 5 are tied together by a horizontal frame member 6. Although the various spaces between the vertical standards are shown as being equal, the widths of the spaces may vary, and, if desired, the intermediate standards may be adjustable laterally so that the widths of the vertical rows of bins may be changed at any time.

At the rear edge of base 2 a plurality of vertical standards 7 extend upwardly in lateral alignment with standards 3, 4 and 5. Standards 8 extend upwardly from base 2 intermediate its depth in lateral alignment with standards 3, 4, 5 and 7. The upper ends of standards 8 are tied together by a horizontal member 9. Standards 8 are also tied to the front standards by horizontal mem-

bers 10 and to the rear standards 7 by horizontal frame members 11 to form a relatively rigid frame work.

Angle irons 12 are arranged in parallel inclined relationship with each secured to a rear standard 7, an intermediate standard 8, and to one of the front standards 3, 4 or 5. A series of vertically aligned angle irons 12 is secured on each side of the intermediate standards 5, and one series of angle irons is secured to the inner sides of each standard 3 and 4. Corresponding angle irons of each series of angle irons lie in a common inclined plane, and each pair of angle irons serve as the base of an individual bin. Each pair of angle irons is adapted to receive packages or boxes 13 of merchandise arranged in a single layer with the front package or box adjacent the front standards, and other packages or boxes lined up behind it in the same plane.

For the sake of convenience, the merchandise will be hereinafter referred to as being boxed, but it will be understood that the dispensing bin is also adapted to handle packages of merchandise wrapped in substantially rectangular form even though no box is provided. Steps 14 are preferably provided adjacent the back side of the frame to facilitate filling the various bins with merchandise. A conventional conveyor 15 is provided at the front of the frame to receive the merchandise as it is dispensed from the various bins and carry it to a wrapping or mailing table (not shown).

A vertical control rod 16 is positioned adjacent standard 4 and each of the standards 5. These vertical control rods are each duplicates, and therefore, only one will be described. Vertical control rod 16 is rotatably secured adjacent the front surface of standard 4 or 5 by means of a plurality of brackets 17. A collar 18 rigidly secured to the upper end of rod 16 is rigidly secured to one end of a link 19. Link 19 is pivotally connected at its opposite end to a link 20 which, in turn, is pivotally connected at its other end to an armature 21 reciprocable in a solenoid 22. A spring 23 mounted in solenoid 22 rearwardly of armature 21 urges the armature outwardly.

A plurality of horizontal restraining levers 24 project laterally from vertical control rod 16 in vertically spaced relationship, with one lever aligned vertically with each of the bins adjacent the vertical control rod. In the normal position of armature 21 each of the restraining levers extends horizontally in front of its particular bin. Armature 21 is controlled by a circuit containing a switch 25. When switch 25 is closed to energize the circuit in which it is wired, armature 21 moves inwardly of solenoid 22, against the action of spring 23, and the linkage 29, 19 rotates control rod 16 to move restraining lever 24 to the dotted line position of Fig. 6 in which the front of the bin is open. Switch 25 is preferably of the push button type that will remain closed as long as it is held down, and will break the circuit as soon as it is released. When switch 25 is released, spring 23 moves armature 21 outwardly of solenoid 22, causing linkage 20, 19 to return restraining lever 24 to its normal obstructing position in front of its bin. It will be obvious that each time vertical control rod 16 is rotated, each of the horizontal restraining levers 24 projecting from the control rod will move simultaneously to open or to package restraining position. Even though all of the restraining levers adjacent one vertical row of bins are open at the same time none of the boxes will move out of its bin because each of the bins is obstructed by its horizontal control rod 26.

A horizontal control rod 26 is provided for each horizontal row of bins. Each rod 26 is a duplicate, and, therefore, only one will be described. Rod 26 is positioned adjacent the bottom of the horizontal row of bins and is journaled in apertures provided therefor in each of standards 3, 4 and 5. One end of rod 26 extends through standard 4 and a collar 27 is rigidly secured thereto. A link 28 rigid with collar 27 is pivotally connected to one end of a link 29. The other end of link 29 is pivotally connected to an armature 30 reciprocable

in a solenoid 31. A tension spring 32 has one end secured to a stud 33 projecting from standard 4 and its other end secured to link 28 to normally hold armature 30 in its outermost position relative to solenoid 31. Armature 30 is controlled by a circuit containing a switch 34, similar to switch 25.

Rod 26 does not project above the bottom of the opening of the bins adjacent which it is positioned, but is provided with a plurality of cams 35 which do project above the bottom of the bins in one position of the rod. Cams 35 are in the form of collars secured rigidly to rod 26 in lateral alignment with each bin of the horizontal row of bins adjacent the rod. In the normal position of rod 26 each cam 35 extends upwardly to obstruct the front of the adjacent bin sufficiently to prevent a box 13 from sliding out of the bin. When switch 34 is pressed downwardly to energize the circuit in which it is wired, armature 30 is moved upwardly into solenoid 31 against the action of spring 32, thereby rotating horizontal control rod 26 to move cams 35 out of the way of the boxes 13 so that the front box, if not otherwise restrained, may slide from the bin and fall by gravity on to conveyor 15. As soon as switch 34 is released, the circuit is open, and spring 32 moves link 28 to rotate rod 26 into its normal position in which cam 35 projects upwardly to engage the front box 13 of each bin in the horizontal row to prevent it from moving out of the bin.

The method of operating the dispensing bin is very simple. Referring to Fig. 2, suppose that it is desired to obtain one box 13 from the uppermost bin in the right hand vertical row. Switch 25 is pressed down to energize the solenoid actuating the vertical control rod 16 adjacent standard 4. Solenoid 22 pulls armature 21 inwardly to rotate rod 16 counterclockwise. Such rotation of rod 16 moves each of its horizontal restraining levers 24 outwardly from its normal restraining position into open position. Although each bin of the right hand vertical row of bins is open insofar as levers 24 are concerned, no box 13 can move from its bin because each box is restrained by the cam 35 of one of the horizontal control rods 26.

Switch 25 is held down to keep levers 24 out of the way of the selected row of boxes, and switch 34, adapted to energize the solenoid actuating the horizontal control rod of the top horizontal row of bins, is pressed down to energize its solenoid 31 and then quickly released. The momentary energization of solenoid 31 causes cams 35 of the uppermost horizontal control rod 26 to rotate downwardly out of engagement with boxes 13. In each of the four vertical rows from the left, the uppermost bins are still obstructed by the levers 24 in their respective rows. In the right hand vertical row of bins the uppermost bin is open, because of the open position of its lever 24, and box 13 immediately starts sliding downwardly over cam 35 by force of gravity.

As soon as switch 34 is released, uppermost rod 26 is rotated back to its normal position by spring 32, cam 35 is moved back to its upper position. Because box 13 has already moved downwardly in its bin, cam 35 moves upwardly into engagement with the bottom of the first box 13 rather than with its front. The slope of angle irons 12 is great enough so that box 13 continues to slide over cam 35, even in its uppermost position, and drops on to conveyor 15. As the next box 13 moves downwardly, in the rear of the dispensed box, its lower front edge is engaged by cam 35 and held thereby against further movement.

Switch 25 is then released, and levers 24 again move in front of the right hand vertical row of bins. The dispensing operation is very fast and merchandise may be moved from the bins much more rapidly than by manual means. If switch 25 is released before the selected box 13 falls out of its bin no harm is done, because restraining lever 24 will move into engagement with the side of the selected box but will not stop its

downward movement. If several boxes 13 are to be dispensed from a single vertical row of bins, switch 25 may be kept depressed while each of the requisite horizontal control rods is actuated in rapid succession. As each box 13 falls on to conveyor 15 it is moved out of the way of the next box so that none of the boxes will fall on a box previously dispensed.

Although the above described method of operation appears to be the most efficient, it is possible if desired, to actuate the horizontal control rod first and to hold cams 35 in open position until the vertical control rod is actuated.

While I have described a preferred embodiment of my invention in considerable detail, it will be understood that the description thereof is intended to be illustrative, rather than restrictive, as many details may be modified or changed without departing from the spirit or scope of the invention. Accordingly, I do not desire to be restricted to the exact construction described.

I claim:

1. A dispensing bin structure comprising a plurality of individual bins aligned horizontally and vertically, a horizontal control rod mounted adjacent each horizontal row of bins, each of said horizontal control rods normally obstructing the front of each bin in the adjacent horizontal row, a vertical control rod mounted adjacent each vertical row of bins, each of said vertical control rods normally obstructing the front of each bin in the adjacent vertical row, and means for selectively operating each of said control rods to move any one of said vertical control rods from its obstructing position, to move any one of said horizontal control rods from its obstructing position while said one vertical control rod is removed from its obstructing position, and to return said one vertical control rod and said one horizontal control rod to said obstructing positions.

2. A dispensing bin structure comprising a plurality of individual bins aligned horizontally and vertically, a horizontal control rod mounted adjacent each horizontal row of bins, each of said horizontal control rods normally obstructing the front of each bin in the adjacent horizontal row, a vertical control rod mounted adjacent each vertical row of bins, each of said vertical control rods normally obstructing the front of each bin in the adjacent vertical row, individual solenoids operable to move each of said control rods out of its obstructing position, means for selectively energizing two of said solenoids to move any one of said vertical control rods out of its obstructing position and any one of said horizontal control rods out of its obstructing position while said one vertical control rod is out of its obstructing position, and means for returning each of said control rods to its obstructing position upon deenergization of its solenoid.

3. A dispensing bin structure comprising a plurality of individual bins aligned horizontally and vertically, each of said bins having an open front and being inclined to dispense boxed or packaged merchandise through said front by gravity, a horizontal control rod mounted adjacent each horizontal row of bins, each of said horizontal control rods normally obstructing the front of each bin in the adjacent horizontal row, a vertical control rod mounted adjacent each vertical row of bins, each of said vertical control rods normally obstructing the front of each bin in the adjacent vertical row, and means for selectively operating any one of said vertical control rods to move it from its obstructing position and for selectively operating any one of said horizontal control rods to move it out of its obstructing position while said one vertical control rod is out of its obstructing position, and to return said one vertical control rod and said one horizontal control rod to said obstructing positions.

4. A dispensing bin structure comprising a plurality of individual bins aligned horizontally and vertically,

each of said bins having an open front and being inclined to dispense boxed or packaged merchandise through said front by gravity, a horizontal control rod mounted adjacent each horizontal row of bins, each of said horizontal control rods normally obstructing the front of each bin in the adjacent horizontal row, a vertical control rod mounted adjacent each vertical row of bins, each of said vertical control rods normally obstructing the front of each bin in the adjacent vertical row, individual solenoids operable to move each of said control rods out of its obstructing position, means for selectively energizing two of said solenoids to move one of said vertical control rods out of its obstructing position, to hold it out of said obstructing position, and move one of said horizontal control rods out of its obstructing position while said one vertical control rod is held out of its obstructing position, and means for returning each of said control rods to its obstructing position upon deenergization of its solenoid.

20 5. A dispensing bin structure comprising a plurality of individual bins aligned horizontally and vertically, each of said bins having an open front and being inclined to dispense boxed or packaged merchandise through said front by gravity, a horizontal control rod rotatably mounted adjacent the bottom of each of said horizontal rows of bins, a plurality of cams mounted on each of said horizontal control rods, each of said cams being laterally aligned with the open front of an individual bin, said cams normally projecting upwardly from said control rods into obstructing position relative to the open front of the adjacent individual bins, means to selectively rotate each of said control rods to move said cams out of said obstructing position, a vertical control rod mounted adjacent each vertical row of individual bins, each of said vertical control rods normally obstructing the open fronts of each individual bin in one vertical row of bins, and means to selectively actuate said vertical control rods to move said vertical control rods out of and back to obstructing position.

40 6. A dispensing bin structure comprising a plurality of individual bins aligned horizontally and vertically, each of said bins having an open front and being inclined to dispense boxed or packaged merchandise through said front by gravity, a horizontal control rod mounted adjacent each horizontal row of bins, each of said horizontal control rods normally obstructing the front of each bin in the adjacent horizontal row, means to selectively actuate said horizontal control rods to move them out of and back to obstructing position, a vertical control rod rotatably mounted adjacent each vertical row of bins, a plurality of horizontal restraining levers projecting laterally from each of said vertical control rods, each of said restraining levers normally obstructing the open front of one of said individual bins in the vertical row of bins adjacent one of said vertical control rods, and means for selectively rotating each of said vertical control rods to move said horizontal restraining levers into or out of obstructing position.

7. A dispensing bin structure comprising a plurality of individual bins aligned horizontally and vertically, each of said bins having an open front and being inclined to dispense boxed or packaged merchandise through said front by gravity, a horizontal control rod rotatably mounted adjacent the bottom of each of said horizontal rows of bins, a plurality of cams mounted on each of said horizontal control rods, each of said cams being laterally aligned with the open front of an individual bin, said cams normally projecting upwardly from said control rods into obstructing position relative to the open front of the adjacent individual bins, individual solenoids operable to selectively rotate each of said horizontal control rods to move said cams out of said obstructing position, means to move each of said cams back to obstructing position upon deenergization of its solenoid, a vertical control rod rotatably mounted adjacent each vertical row of bins, a

plurality of horizontal restraining levers projecting laterally from each of said vertical control rods, each of said restraining levers normally obstructing the open front of one of said individual bins in the vertical row of bins adjacent one of said vertical control rods, individual solenoids operable to selectively rotate each of said vertical control rods to move said restraining levers out of obstructing position, and means to rotate said vertical control rods in reverse direction upon deenergization of said second mentioned solenoids to move said restraining levers back to obstructing position relative to the front of said bins in each vertical row of bins.
